WELL PUMPING CONTROL

Benjamin H. Urmann, Ridgeway, and Albert J. Whitehill and Wayne H. Thessen, Bradford, Pa.; said Urmann assignor to said Thessen

Application July 12, 1950, Serial No. 173,342

14 Claims. (Cl. 103—25)

1

This invention relates to well pumping control.

The invention is particularly adaptable for the control of so-called non-flowing wells. The particular type of well is the drilled type and wherein the conventional casing, tubing, sucker rods, valves and pumping mechanisms, etc. are utilized. The pumping control embodied in this invention is adaptable for use in combination with the aforesaid conventional component elements of a well and the pumping mechanisms therefor. The purpose of the present invention is to automatically initiate the pumping operation of the well and to continue the same so long as there is a supply of oil or other liquid available in the well and, when such supply has been pumped to automatically discontinue the pumping operation, and wherein such automatic starting and stopping of the pumping operation is controlled by and depends upon the presence or absence of liquid in the well to be pumped.

There have been many attempts to provide some means or mechanism to automatically set into operation the pumping of a well or wells. One of such attempts is by means of a timer such as a clockwork mechanism which can be preset to effect a pumping operation of a well through one or more cycles of operation of the timing mechanism. These operating cycles for the pumping of the wells, therefore, take place whether or not there is any liquid in the well to be pumped. Under these circumstances, of course, power for operating the pumping mechanism is being utilized and wasted and, moreover, when the pumping mechanism is in operation and there is no oil or water or other liquid available in the well to be pumped, this has a very detrimental effect on future production of the well. In a situation where a well or wells are adjacent the border of two adjoining oil bearing fields, and assuming that a well or wells had accumulated oil therein that should have been pumped and was not pumped, then, as aforesaid, this oil in the particular strata bearing the oil sands or the like, would then be available to and flow into the well or wells on the adjoining property where such wells are in operation. Thus, the owner of the property would be deprived of the oil that had accumulated in the well and was not pumped and this is what happens in connection with the timing control operation of wells.

Devices, such as floats and pumps have heretofore been positioned within a drilled well and purportedly for the purpose of automatically de-

2

termining when the well should be pumped and when oil, of course, is present. The difficulty experienced with these two types of well pumping control is that, primarily, it is rather difficult, if not impossible, to provide a float that would be efficient several hundreds of feet below the ground surface to control the pumping operating mechanism for the well and, moreover, the problem exists as to how to protect the float from being blown up or collapsed in view of the pressure that exists within the well.

There have been many attempts to control the well pumping operations and, while all of the attempts previously made are partially satisfactory, there are many objections thereto.

We have provided a device which consists of a minimum number of cooperating component elements and where there are a relatively few movable parts. Our device consists of a single unit that is readily associated with the tubing of the well or positioned adjacent the tubing of the well. This device, as aforesaid, is a single unit and may be sealed, preset as to be operated by a predetermined pressure within the well. The device is electrically and mechanically or otherwise associated with the well pumping operating mechanism and, when positioned in the well, automatically controls the functioning of the well pumping apparatus or mechanism.

The device is initiated by the pressure conditions within the well and, only under such circumstances, where oil or other liquid has accumulated in a sufficient quantity to call for a setting into operation the said well pumping mechanism, and this is accomplished automatically and when the accumulated supply of oil or other liquid has been pumped from the well, the device then will automatically discontinue the operation of the well pumping mechanism or apparatus and this pumping operation and discontinuing of the same is repeated automatically when the presence of oil in the well sets the device into operation to effect the control of the well pumping mechanism or apparatus, and, likewise, accomplishes the reverse in discontinuing the operation when the liquid supply has been pumped from the well.

The size and shape of our unitary well pumping control unit or device is such that it may be readily positioned in or removed from a well as the case demands. The device includes certain sealed instrumentalities which are in cooperative relationship with one another so as to effect an electrical control of the well pumping apparatus or mechanism. This electrical con-

trol is initiated solely by the presence of a liquid in the well that is to be pumped. In the absence of any liquid in the well, the device and the electrical control are in an inoperative condition.

With the above in mind, it is an object of our invention to provide a device for controlling the pumping of wells, which mechanism is placed within the well and is connected with the pumping operating mechanism exteriorly of the well, and is set into operation by the presence of sufficient liquid within the well that is to be pumped.

Another object of our invention is the provision of means placed within a well which automatically controls the well pumping apparatus exteriorly of the well, and which means is solely initiated by pressure conditions within the well, which determine whether or not the well pumping mechanism is operating or inoperative.

Another object of our invention is to provide a device for controlling the pumping operation of a well, which device includes a sealed component element, which element is caused to function by the pressure conditions within a well and where a liquid supply has accumulated therein, and this component element, in turn, effecting operation of electrical means in a circuit and which circuit includes the well pump operating mechanism so that when the said sealed component element functions, the electric circuit is controlled, and when liquid has accumulated, the circuit is closed and the well pumping is functioning and, in the absence of liquid, the circuit is open and the well pumping mechanism is inoperative.

Another object of our invention is to provide a device for automatically controlling the well pumping apparatus or mechanism, and which device and its cooperative component elements are such that it is sufficiently rigid to withstand handling and connecting and disposing of the same within the well, and that the said device and the component elements possess such inherent characteristics as to prevent any accidental dislocation or rupturing of the elements due to handling and/or pressure conditions within the well.

With the above and other objects in view, the invention consists in the construction and novel combination and arrangement of parts herein-after fully described, illustrated in the accompanying drawings and pointed out in the claims hereto appended, it being understood that various changes in the form, proportions, and minor details of constructions, within the scope of the claims, may be resorted to without departing from the spirit or sacrificing any of the advantages of the invention.

In the drawings:

Fig. 1 is a view in elevation showing our device positioned in a well.

Fig. 2 is a vertical sectional view taken substantially along the lines 2—2 of Fig. 1;

Fig. 3 is a vertical sectional view taken substantially along the lines 3—3 of Fig. 1;

Fig. 4 is a vertical sectional view taken substantially along the lines 4—4 of Fig. 1;

Fig. 5 is an elevational view of the device with the casing removed;

Fig. 6 is a perspective view of one component element of the device;

Fig. 7 is a transverse sectional view taken substantially along the lines 7—7 of Fig. 1;

Fig. 8 is a modification of the device;

Fig. 9 is an elevational view similar to Fig. 1 showing a further modification of the device;

Fig. 10 is a diagrammatic illustration of the electrical circuit in which our device is included and the circuit also including the motor for operating the well pumping mechanism or apparatus; and

Fig. 11 is an elevational view of a tank for a liquid or air under pressure, and which tank is utilized to preset the device referred to in the other figures of the drawings.

The invention will be more readily understood by referring to the drawings in detail wherein the same numerals or characters used in the several figures all denote the same parts or component elements.

In Figs. 1 and 9 of the drawings, there is disclosed a conventional drilled well. The depth of the drilled well is indefinite in that the same varies depending upon the geological formation and the depth to which the well is drilled to reach an oil bearing strata. The different strata of the earth is denoted by the numerals 1 through 6 and, of course, the stratas of earth vary in the different regions of the country. As shown, the oil bearing strata is denoted at 4 and it is in this oil bearing strata of earth that the enlarged shot hole 7 is formed in the conventional manner. Above the shot hole and connected therewith, there is a substantially cylindrical bore 8 and, likewise, below and connected with this shot hole there is a substantially cylindrical pocket 9.

After the well has been drilled or otherwise formed and the shot hole formed therein in the oil bearing strata of earth, the usual and conventional drive pipes, casing, tubing, sucker rods, etc. are placed within the well. The drive pipe, which is the uppermost pipe in the well, is denoted at 10 and the top thereof ordinarily extends slightly above the surface of the earth. Concentrically arranged within this drive pipe, and in spaced relation thereto, the casing 11 is inserted, and concentrically within this casing 11 and in spaced relation thereto, the tubing 12 is positioned. It is understood, of course, that the drive pipe and the casing may be in the form of end to end connected sections and, likewise, the tubing 12 is in the form of end to end sections, and which sections are secured together by a plurality or series of interiorly screw threaded conventional couplings 13. A working barrel 14 is connected adjacent the end of the tubing 12 by means of a coupling 15 and below this working barrel and connected therewith is a perforated substantially cylindrical pipe or strainer 16. Our device indicated generally at D for controlling the well pumping operating mechanism is connected with the perforated strainer 16 by means of a coupling 17 and a so-called anchor 18 which is in the form of a perforated cylindrical pipe which acts as a strainer is connected at 19 with the said device. A plug 20 closes the free end of the anchor 18 and it will be noted that the free end of this anchor extends above and in spaced relation to the bottom 21 of the pocket 9.

There is a usual cap or head of the well 22 which is mounted on the end of the casing 11 that extends above the surface of the earth. The sucker or pumping rods 23 that are connected in a series and which, of course, are conventional well appurtenances, are disposed within the tubing 12 concentrically and in spaced relation therewith. On the end of the lowermost sucker rod 23 in the well, there is an interiorly screw threaded socket 24 into which the exteriorly screw threaded stud 25 at the upper end of the conventional sliding valve 26 is secured. This

sliding valve 26 operates in the working barrel 14, the interior surface of which barrel is machined and smooth. The valve 26 includes the usual series of spaced cup washers 27 and the usual valve cage 28 and valve seat 29 and the ball valve 30. Also disposed in the working barrel 14 is the conventional standing valve 31 and this valve, too, includes the usual cup washers 32, valve cage 33, valve seat 34 and the ball valve 35. This valve 31 is, of course, stationary in the working barrel 14 and is maintained at its lower end 36 on an inwardly projecting seat 37 that is either integral with or applied to the interior of the lower portion of the working barrel 14.

In Fig. 10, there is diagrammatically illustrated a conventional wiring diagram and well pumping operating mechanism. The wiring circuit is the usual or conventional three-phase system and includes the three wires 38, 39 and 40 and the connected multiple manually operable switch 41, the solenoid 42 for operating the solenoid controlled multiple switch 43 and which includes a spring 44. The circuit additionally includes wires 45 and 46 in which suitable fuses 47 are utilized in connection with the transformer 48 and another manually operable switch 49 and a micro switch 50. The three wires 38, 39 and 40 are connected with an electric motor M. This electric motor is supported on a platform P and the motor has on its shaft a pulley 51 preferably of the V-type with a V-type belt 52 trained thereover and also over another pulley 53 which is supported on the bracket 54 and includes a shaft on which gear 55 is mounted and which gear 55, in turn, engages a relatively larger gear 56 and which gear has concentrically attached thereto a crank arm 57 and one end 58 of this crank arm is attached to a walking beam or jack 59 which is pivotally mounted at 60 to a supporting structure 61 which supporting structure, in turn, is mounted on and carried by the platform P. There is a counterbalance weight 62 that is adjustably mounted at one end of the walking beam 59 and, at the other end, there is a head 59' that connects with the pumping or sucker rod 23.

The foregoing elements, the electrical circuit and the cooperable means for effecting the pumping operation, as well as the formation of the well, are all well-known and conventional except for the micro switch 50 which is referred to specifically hereinafter.

Our device for controlling the well pumping operating mechanism indicated generally at D consists of an elongated substantially cylindrical exterior casing or housing 63, one end 64 of which is exteriorly screw threaded and the other end portion thereof 65 is preferably reduced in cross section and is, likewise, exteriorly screw threaded as at 66. The coupling 17, which is screw threadedly engaged with the perforated strainer pipe 16, differs from the couplings 13 in that it includes a solid partition 17' substantially intermediate its ends and this coupling is interiorly screw threaded as at 67 and receives therein the exterior screw threads 66 of the reduced end portion 65 of the housing 63 and closes that end of the device D. Of course, the couplings 13 are hollow and have no partition therein. An interiorly threaded elongated coupling 68 has a portion of its threads engaged with the exterior thread 64 on the lower end of the housing or casing 63. Within this interiorly screw threaded coupling 68, there is disposed a counterbore plug 69 which has an exterior portion thereof 70 provided with screw threads and a continuing exte-

rior portion thereof 71 that is preferably knurled or otherwise roughened so as to afford a grip thereon. This plug 69 has one portion thereof 72 counterbored and interiorly screw threaded and this screw threaded formation is substantially centrally of the plug. There is a recess 73 defined centrally of the plug and this recess terminates in an opening 74 preferably of less diameter than the said recess and the walls of this opening 74 are interiorly screw threaded as at 75. The plug 69 has an upper flat seating surface 76 which is substantially circular in outline. This surface 76 has thereon a ring-like sealing washer 77.

In Fig. 10, there is diagrammatically illustrated a conventional wiring diagram and well pumping operating mechanism. The wiring circuit is the usual or conventional three-phase system and includes the three wires 38, 39 and 40 and the connected multiple manually operable switch 41, the solenoid 42 for operating the solenoid controlled multiple switch 43 and which includes a spring 44. The circuit additionally includes wires 45 and 46 in which suitable fuses 47 are utilized in connection with the transformer 48 and another manually operable switch 49 and a micro switch 50. The three wires 38, 39 and 40 are connected with an electric motor M. This electric motor is supported on a platform P and the motor has on its shaft a pulley 51 preferably of the V-type with a V-type belt 52 trained thereover and also over another pulley 53 which is supported on the bracket 54 and includes a shaft on which gear 55 is mounted and which gear 55, in turn, engages a relatively larger gear 56 and which gear has concentrically attached thereto a crank arm 57 and one end 58 of this crank arm is attached to a walking beam or jack 59 which is pivotally mounted at 60 to a supporting structure 61 which supporting structure, in turn, is mounted on and carried by the platform P. There is a counterbalance weight 62 that is adjustably mounted at one end of the walking beam 59 and, at the other end, there is a head 59' that connects with the pumping or sucker rod 23.

The foregoing elements, the electrical circuit and the cooperable means for effecting the pumping operation, as well as the formation of the well, are all well-known and conventional except for the micro switch 50 which is referred to specifically hereinafter.

The abutment 96 is fixedly positioned in and carried by a frame that consists of elongated spaced bars or straps or the like 98, 99 and 100. Each of these bars is fixedly secured by means of screw threaded bolts or the like 101 in different diametric positions about a boss 102 that is integral with the plug 69 and is upstanding substantially centrally thereof. The abutment 96 is secured to the said bars or straps by means of suitable screw threaded bolts 103 and this abutment is above the coil spring S, see Figs. 2 and 5. The upper ends 104 of the said straps or bars are each secured by means of screw threaded bolts 105 to a rigid disc 106, and which disc is of substantially the same diameter as the boss 102. Thus, the said bars or straps or the like 98, 99 and 100 being of rigid metal or the like, are, therefore, rigidly connected with, supported on or carried by the plug 69. The upper portion 93 of the valve stem 84 passes through and beyond the opening 97 in the abutment 96 and secured to the screw threaded end portion thereof there are suitable interiorly screw threaded adjustment stop nuts 107 and 108. A switch operating arm 109, which is a substantially flat strip of metal or the like, is slotted as at 110, and one

end thereof 111 is at a substantially right angle thereto and is provided with an opening 112 through which the screw threaded reduced end portion 95 of the valve stem 84 of the valve projects. The adjustable stop members 107 and 108 grip upper and lower faces of the right angularly extending portion 111 of the switch operating arm 109. This switch operating arm 109 is slidably carried on the frame member 100.

Suitable studs 113 have their ends 114 swaged or otherwise fixedly disposed in openings in the frame member 100 and these studs extend laterally from this frame member or at a right angle thereto in vertically spaced relationship and each stud has a coil spring 115 concentrically thereabout, and one end of each of these coil springs bears against a washer 116 and the other end of each spring bears against a similar washer 117 and each of these last mentioned washers is maintained in position with respect to the 10 stud by means of cotter keys or the like 118 which pass through openings 119 in the studs. Thus, the switch operating arm 109 is frictionally maintained against the confronting flat surface of the frame strap member 100. The extreme 15 upper end 120 of the switch operating arm 109 is turned slightly inwardly and is disposed in the path of the flat spring arm 121 that is integrally attached to the micro-switch 59. This micro-switch 59 is fixedly attached to a depending bracket 122 that is integral with the top disc frame element 106 and in which member there is a centrally disposed opening 124. One end 125 of an electrical conductor 126 is electrically connected with the micro-switch 59 and this electrical conductor may be wound about or otherwise secured as at 127 to the upwardly extending part 128 of the frame member 100. The 20 portions of the casing or housing 63 above the micro-switch and the frame that carries the same, is preferably recessed at 129 and this recess has an opening 130 therein through which the conductor 126 extends and this conductor is held in the recess by means of a split compressible plug 131 that is mounted on the said conductor and engaged in the recess.

In order to prevent the cable from becoming entangled with our device or the other component elements when inserting the same in the well, or while it is disposed therein, or in removing the same therefrom, there is preferably provided a plurality of substantially disc-like combined spacer and cable holding members 132 which can be split, if desired, but if not, the same simply are positioned about the sections of the tubing adjacent the couplings 13 and 15. These spacers are provided with cut-out portions 133 substantially of keyhole formation and of sufficient size so that the conductor 126 can be deposited therein, and this conductor is held in the said slot by means of a split and tapered plug 134 which surrounds the cable and which plug, of course, enters into the said slot. The combined spacer and conductor holding disc may be held in fixed association with the well tubing in any suitable manner and a wedge 135 that engages in the opening 136 and a portion of the wall of the tubing 12 serve effectively to maintain these discs in their proper position. The cable extends up to and out of the head or cap of the well, of course, and is connected in the wiring diagram illustrated in Fig. 10.

An expansion tube denoted generally at 137 is connected with the plug 69 of the device. This expansion tube includes two connected legs 138

5 and 139 and the bottom thereof is closed at 140 and has a removable plug 141 screw threadedly positioned therein. The upper end of the expansion tube is screw threaded as at 142 and this screw threaded end is interengaged with the screw threads 75 in the opening 74 of the plug 69. This expansion tube, as will be seen in Fig. 3, extends into the perforated anchor 18 and the closed bottom 140 thereof is spaced above the plug 20. A liquid such as used in hydraulic braking systems or any suitable liquid is entered into the expansion tube 137 by means of inverting the same and pouring through the opening closed by the plug 141. This liquid, whether it be inserted in the expansion tube or whether it be the oil or water or any other liquid in the pocket in the well, serves as hereinafter more fully described to effect functioning of our device.

In the modification of the invention as depicted in Fig. 8 of the drawings, the bellows assembly 143 is used in place of the pressure tube assembly 137. This bellows assembly consists of opposite caps 144 and 145. The cap 144 to which one end of the bellows is secured as by welding, soldering or the like, or in any other suitable manner, has a hollow bored shank 146 therethrough and the exterior part 147 of this shank is exteriorly screw threaded and these screw threads engage in the screw threads 75 in the plug 69. The cap 145 is secured to the other end of the bellows as by welding, soldering, etc. and it, too, has a central bore or passageway 148 therein and a part of which is interiorly screw threaded at 149 and closed by an exteriorly screw threaded plug 150.

It is evident, therefore, that we may either utilize the pressure tube 137 which, incidentally, is open at one end as at 137', or the bellows assembly 143 as shown in Fig. 8, as either of these devices is interchangeable. In utilizing the bellows assembly 143, the liquid, of course, is introduced through the opening 143 and is sealed and closed in this bellows 143 and also in the bellows 86. This, of course, contrasts with the pressure tube 137 which is open at one end 137'.

In the modification of the invention as depicted in Fig. 9 of the drawings, instead of connecting our device for controlling the well pumping operating mechanism in the tubing line 12, here, we simply connect our device D in a separate line of tubing 151 and which separate line of tubing substantially parallels the well tubing 12. In utilizing the invention as shown in Fig. 9, the anchor 152 at the bottom of the tubing is simply of greater length than that shown in Fig. 1, but there is an anchor 153 that is attached by means of the coupling 154 to our device D and this anchor is perforated as at 155. It is understood that the device D shown in Fig. 9 contains all of the cooperative component elements and the various instrumentalities that have been described in connection with Figs. 1 through 6, and that the device as shown in Fig. 9 functions in 55 precisely the same manner as the same does in connection with the device as shown and described in connection with Fig. 1 through 6, both inclusive. In utilizing the separate pipe line 151, as shown in Fig. 9, however, the electrical cable or conductor 126 is connected with the micro-switch 59 and extends throughout the length of this tubing 151 and beyond the upper end thereof and is connected in the circuit as disclosed in Fig. 10 and hereinbefore described. The pipe line 151 may, of course, include the necessary

couplings 151 for the sections constituting this said pipe line.

In Fig. 11, there is disclosed a container 156 which may be cylindrical or of any other outline and hollow, of course. This container is supported on and carried by a base 157. Extending outwardly from the container, there is a conventional valve stem 158 within which there is the usual Schrader tire valve, not shown. The top 159 of the container is, of course, closed, and extending upwardly therefrom, there is an integral hollow nipple 160 into which the short extension of pipe 161 is screw threaded. The free end 162 of this pipe 161 is exteriorly screw threaded and the screw threads are of the same circumference and pitch so as to be received and connected with the screw threads 75 in the opening 74 of the plug 69 for a purpose hereinafter described. Additionally, the container 156 carries an air pressure gage 163 thereon. This container 156 is adapted to contain air under pressure. The air is entered thereinto through the valve stem 158 and the amount of pressure that is built up is indicated on the pressure gage 163. Air under pressure is forced into the said container 156 from any suitable source and, when the screw threads 162 are engaged in the said screw threads 75 of the plug 69, and, of course, before the device is inserted within a well, the desired amount of air pressure as indicated by the gage 163 is thereby released against the valve 80, which valve is open due to the pressure of spring S against the bellows 86, this being a downward pressure when the device is viewed as in Fig. 2. By means of this air pressure released from the container 156, therefore, and assuming that the adjustable stops 107 and 108 have been released or moved away from the right angularly extending arm 111, the air pressure against this bellows which shows on the gage 163 is, of course, determined and this allows a predetermined setting of the switch as regards its opening and closing movements. The bellows, when the device is in the well, has pressure exerted thereon either directly from the liquid in the pressure tube 137 or indirectly by the liquid that is sealed between the two bellows 86 and 143 as seen in Fig. 8. It is this pressure of the liquid that is placed in the pressure tube or between the two said bellows or the liquid from the well itself, as regards the invention as shown in Fig. 1 and Fig. 6, that effects the operation of the valve 80.

When the device, as a whole, is inserted in the well and there is no accumulated liquid in the well to be pumped, then the valve 80 is open. However, when there is an accumulation of liquid within the well to be pumped beyond the safety capacity of the bellows, our device has functioned to initiate the starting of the well pumping mechanism, then this valve 80, due to the pressure of the liquid in the well, is closed, and remains closed during the pumping period, until the pressure drops below the safety range of the bellows. Thus, it is clear that, if there is no accumulated liquid in the well to be pumped, the valve 80 is open and there is no action whatsoever imparted from this valve to the switch operating rod and to the micro-switch 50 and there is no pumping operation whatsoever, but, as the liquid builds up or accumulates in the shot hole 7 of the well, above the liquid level indicated in Fig. 1, then the pressure of that accumulated liquid will cause the bellows to compress. Consequently, upon upward movement of the valve

stem 80 and a corresponding movement of the switch operating arm 169, this switch operating arm effects operation of the micro-switch 50 which is in the circuit, as shown in Fig. 10, and, thus, the pumping apparatus or mechanism is brought into action to perform the pumping of the well.

Reference to liquid in the specification and claims, of course, means either oil or water or a combination of same that may be in the well and, of course, the chemical ingredients that are present in or along with the water or oil.

From the foregoing, it is clear that, if the well pumping operating mechanism, as disclosed in Fig. 10, is supplied with electrical current through the circuit and there is an excessive accumulation of liquid within the shot hole 7, the valve 80, under such circumstances, will be closed and the micro-switch 50 will have been operated and this switch being in the aforesaid electrical circuit, will allow the electric motor M to operate and, in turn, through the crank connection to the walking beam, will effect pumping of the well by means of reciprocation of the sucker rods 23. Incidentally, during the pumping operation, on the downstroke of the sliding valve 25, the ball valve 30 will be in the upper part of the cage and consequently, off of the valve seat 29; whereas, the ball valve 35 in the standing valve 31 will be on its seat 34 and, consequently, closed, and the reverse takes place when the sliding valve 25 moves upwardly in the barrel 14; namely, that the valve 35 will be off of its seat 34 whereas the valve 30 in the sliding valve 25 will be on its seat 29. Thus, the oil, water or other liquid is pumped up through the tubing 12.

It has been mentioned hereinbefore the difficulty of preventing detrimental and injurious effects upon the prior art devices for controlling the pumping of wells. In connection with our invention, such injurious and detrimental effects are positively overcome in that the bursting or blowing up of the bellows 86 and the other bellows 143, and any of the valve mechanism, is prevented. This is accomplished, as aforesaid, during the pumping operation, when excess pressure exists, because the valve 80 is closed and, thus, no pressure within the well is allowed to enter either of these bellows and, consequently, cannot disrupt or blow the same. This provides a safety measure against any blowing out of the bellows or the valve parts associated therewith. It will be readily seen that, if the valve 80 were not provided, the liquid pressure within the well, due to an accumulation of liquid therein, would disrupt and blow out this bellows and, consequently, the control device would, therefore, not perform its function for controlling the well pumping operating mechanism.

It is evident that we have constructed a novel unitary device for controlling well pumping operating mechanisms and that the said device can be associated either directly in the line of tubing in the well or can be positioned separately and distinct apart from this tubing in the well, as shown in Fig. 9 of the drawings. Then, too, our device is such that the main component elements thereof can readily be prefabricated and all associated together and, as such, readily received thereabout a protective casing, and a unit as a whole can be handled for insertion in or removal from the well as the occasion demands. Additionally, we have provided the compact and novel sub-assembly of the bellows and spring loaded valve arrangement as shown in Fig. 6 of

the drawings which, as a unit, can be associated with the device as shown in Fig. 5 of the drawings. Wherever there are screw threaded connections in our device, the pitch of the threads is such as to form a leak-proof joint therebetween.

In addition to our device performing its function for controlling the well pumping operating mechanism, the same also functions admirably as a gas saver. This is occasioned by the fact that there is always liquid in the pocket 6 up to the indicated liquid level so this liquid, which may be oil or water or a combination of same, indicated at C, prevents the gas from entering the perforated sections 16. Thus, any accumulated gas in the well will pass out through the casing 11 into the head 22 and out through the pipe E for storage or any other use that may be desired. It is to be kept in mind that, as aforesaid, there is always liquid in the pocket 6 and this prevents any outlet of gas through the tubing 12 and, consequently, keeps the gas separated from the liquid, whether it be oil or water or the like, that is being pumped from the well.

The fact that our device functions only when there is liquid to be pumped from the well prevents the pounding and detrimental action that is imparted to the sucker rods as is present in prior well pumping methods. This pumping, when there is no liquid available in the well, is detrimental in that it, after a while, crystallizes the rods and the connections between the same are broken. Thus, it is indeed advantageous to pump the well only when liquid is present or accumulated in the well. It is to be understood that our device functions whenever the liquid, such as oil or the like, accumulates in the shot hole 7 above the liquid level line indicated in Fig. 1. With our adjustable setting means of the operation of the valve 80, this valve can be set to start a pumping operation at any height of accumulation of liquid in the shot hole 7 and, of course, it is preferable to start this pumping operation from the shot hole 7 when the same is substantially full.

The seating of the valve 80 acts to provide a safety valve if the pressure in the hole should exceed the allowable carrying capacity of the bellows. This seating of the safety valve 80 enables us to use the whole structure of the bellows, from compression to expansion, for a wider range of footing or where the fluid in the hole at the time of installation exceeds the capacity of the bellows, or in the case of a power failure. In all these cases, the valve does remain open until the pressure is reached beyond the carrying capacity of the bellows and then the valve closes and shuts out any increase until the well is pumped off to the pressure drop on which the bellows and valve are set to operate. The valve 80, as an example, may be set for about 125 pounds pressure whereas the bellows may be set at 150 pounds pressure. These pressures of presetting the valve and bellows are merely exemplary and may, of course, slightly vary somewhat.

We claim:

1. A device for controlling a well pumping mechanism which includes an electrical circuit, said device being positioned in a well and including an exterior casing, an assembly consisting of a spring loaded safety valve and bellows within the said casing, and said assembly having a valve seat thereon which is adapted to be engaged by said valve, a movable mechani-

cal means adjustably carried by said bellows and valve assembly switch connected in said electrical circuit adjacent the said means, pressure exerting means to effect movement of said bellows, whereby when said pressure is exerted against said bellows and when liquid has accumulated in the well and under such circumstances the bellows is expanded and, in the absence of liquid, the said bellows is compressed and thus the movement of the bellows controls the operation of the well pumping mechanism by means of the said switch in the circuit.

2. A device for controlling a well pumping operating mechanism, said device being a unitary structure and including an outer casing and associated with conventional well equipment and disposed in a well, the casing carrying a movable safety valve assembly adjacent its lower end when in a well, said valve assembly having embodied therewith a bellows and there being a valve stem to which said bellows is fixed and is concentrically disposed with respect thereto, a seat for the said valve, a spring concentrically disposed about said stem and having one end thereof in engagement with the said bellows and the other end against an abutment, thus spring loading the said bellows, and normally tending to compress the said bellows and maintain the valve off of its seat, a circuit maker and breaker within the casing in adjustable spaced relationship with respect to the stem of the valve, valve adjustment means carried by the said valve stem, a connection between the said adjustment means and engageable with the said switch, the said bellows being exposed to liquid pressures within a well and in the absence of such liquid pressure said bellows will remain compressed, but when liquid pressures are present beyond the safety limits of the bellows the valve will close on the seat and effect operation of said switch, the switch being in an electrical circuit that includes the well pumping operating mechanism, and when the said switch is operated by movement of said bellows, the said mechanism is controlled so as to properly perform its function.

3. A device for controlling well pumping operating mechanism which is unitary in character and, as such, inserted in a well and subject to the pressure conditions within the well, the said device including a casing, a spring loaded bellows assembly in the casing, the bellows assembly including a valve, a valve stem and a seat for said valve, the bellows being concentrically disposed about said valve stem and exposed to the compressive forces of said spring, another bellows having liquid therein, which liquid is effective for controlling the opening and closing of said valve, the last mentioned bellows being sealed and exposed to liquid pressure conditions within a well and when this last mentioned bellows is collapsed due to the presence of sufficient liquid pressures within the well, the valve will be maintained on its seat and the first mentioned bellows which is normally partially collapsed by the pressure of said spring will be expanded and under compression of the said spring.

4. A device for controlling well pumping operating mechanism positioned within a well and attached in a tubing line of the well, the well having a shot hole therein and a pocket in communication therewith and therebelow, the said device being positioned in the said pocket, 70 the well operating mechanism including an elec-

trical circuit connected with an adjustable circuit maker and breaker carried by said device, a spring loaded bellows and safety valve assembly carried by said device, the said bellows assembly being subject to pressure conditions created by a liquid accumulated in said shot hole, the said electric circuit maker and breaker being connected with said bellows, whereby upon movement of said bellows by a pressure condition within said well, the same will expand and the well pumping operating mechanism will be initiated by means of operation of said adjustable circuit maker and breaker and accumulated liquid pumped from the shot hole.

5. A device for controlling well pumping operating mechanism including the usual well casing and tubing, sucker rods and valves, all disposed in a conventional manner within a well which includes a shot hole and a pocket therebelow and connected therewith, and also the pumping operating mechanism including an electrical circuit, the device being positioned in the pocket below the said shot hole and having a pipe connection extending outwardly of the top of the well and substantially paralleling the tubing within the well, a safety valve positioned in and carried by the said device, said device being exposed to pressure conditions occasioned by the accumulation of a liquid in the shot hole of the well, the device also including a circuit maker and breaker electrically connected in the said circuit, whereby when the valve is closed due to pressure conditions within the well, the switch will energize the electrical circuit and the well pumping operating mechanism will perform its pumping function to pump the liquid from the well, and in the absence of a liquid within the shot hole of the well, the said pumping operating mechanism will be inoperative.

6. A device for controlling opening and closing of a circuit for an electrically operated apparatus comprising a casing adapted to be mounted vertically and immersed in a column of liquid subject to variations in depth and consequent pressures, a switch in said casing, a mounting member in said casing formed with a vertical bore and with a valve seat about the lower end thereof, a bellows mounted upon said mounting member and having its lower end open and communicating with said bore, a cap closing the upper end of the bellows, a valve movable upwardly to a closed position against the valve seat and having a stem passing vertically through the bore and the bellows and fixed to the cap and projecting upwardly therefrom and engageable with the switch to close the switch when the stem is shifted upwardly by expansion of the bellows and the valve is thereby seated against the valve seat, the valve when engaged with the valve seat sealing the lower end of the bore and thereby limiting increase of liquid pressures in the bellows to which the bellows is subjected.

7. A device for controlling opening and closing of a circuit for electrically operated apparatus comprising a casing adapted to be entirely immersed in a body of liquid subject to variations in depth and consequent pressures, a switch in said casing, actuating mechanism for said switch mounted in said casing and including a stem shiftable upwardly and downwardly in the casing and having its lower portion passing through a bore at the bottom of the casing, a vertically expansible and contractable pressure influenced member in said casing surrounding said stem and having its upper end closed and fixed to the stem,

5 the lower end of the pressure influenced member being rigidly secured about the bore and communicating with the body of liquid through the bore whereby increase in depth and consequent pressure of the liquid will distend the pressure influenced member and move the stem upwardly and close the switch, a valve member carried by said stem and moving upwardly therewith into closing relation to the bore to isolate liquid in the pressure influenced member from the body of liquid as the switch is closed and prevent further distention of the pressure influenced member, and spring means for collapsing the pressure influenced member downwardly and thereby shifting the stem downwardly to open the switch and the valve as pressure of the body of liquid is reduced by lowering the level of the liquid to a predetermined level.

8. A device for controlling opening and closing of a circuit for electrically operated apparatus comprising a casing adapted to be mounted vertically and immersed in a body of liquid subject to variations in depth and consequent pressures, a switch, mechanism for opening and closing the switch including a stem shiftable upwardly and downwardly in the casing, a pressure influenced means in said casing connected with said stem and having an open lower end communicating with the body of liquid whereby the pressure influenced means is responsive to variations in pressure of the liquid and moves the stem in a direction to close the switch as pressure of the liquid increases, and a valve connected with said stem and moved thereby into position to shut off communication between the pressure influenced means and the body of liquid and thereby isolate liquid in the pressure influenced means from effects of increasing pressures of the body of liquid outside the casing after 40 the switch is closed.

9. A device for controlling opening and closing of a circuit for electrically operated apparatus comprising a casing adapted to be immersed in a body of liquid subject to variations in depth and consequent pressures, a switch, mechanism for opening and closing the switch including a stem shiftable upwardly and downwardly in the casing, a bellows in said casing connected with said stem and having an open lower end communicating with the body of liquid whereby the bellows is distendable in response to variations in pressure of the liquid and moves the stem in a direction to close the switch as depth and resultant pressure of the liquid increases, and a valve for shutting off communication between liquid in the bellows and the body of liquid, said valve being connected with the bellows and actuated by expansion and contraction of the bellows and being thereby moved to its closed position in response to expansion of the bellows and closing of the switch.

10. A device for controlling opening and closing of a circuit for electrically operated apparatus comprising a casing adapted to be immersed in a body of liquid subject to variations in depth and consequent pressures, a switch for said circuit, mechanism for closing and opening the switch including an actuating bellows mounted in the casing and having an open end in communication with the body of liquid whereby liquid filling the bellows may cause expansion of the bellows and thereby effect closing of the switch as the depth and resulting pressure of the body of liquid increases, and a valve operatively associated with the bellows and movable thereby

during expansion of the bellows to a closed position shutting off communication between liquid in the bellows and the body of liquid outside the casing when the switch is closed and thus limiting expansive force applied to the bellows by 5 pressure of the body of liquid.

11. A device for controlling opening and closing of a circuit for electrically operated apparatus comprising a casing adapted to be immersed in a body of liquid subject to variations in depth and consequent pressures, a switch for 10 said circuit, operating means for said switch including a bellows in said casing having an open end communicating with a passage through the casing, which passage has an outer end communicating with the body of liquid in which the casing is immersed whereby a portion of the liquid may enter the bellows through the passage and pressure exerted by the liquid in the casing 15 expands the bellows and thereby effect closing of the switch as pressure of the liquid is increased in response to increasing depth of the liquid, and means for closing the passage actuated by expansion of the bellows and moved thereby to a closed position as the switch is closed and thus limit the amount of pressure which may be applied by liquid within the casing to the bellows during increasing depth of the liquid externally 20 of the casing.

12. A device for controlling an electrically actuated pump-operating mechanism comprising a casing adapted to be submerged vertically in a body of fluid subject to variations in depth and consequent pressures, said casing having an inlet and a valve seat associated therewith, a spring 30 loaded valve movable inwardly of said casing to a closed position against the valve seat and urged outwardly to an open position, a pressure responsive member in said casing enclosing the inlet and connected with the valve and serving to shift the valve to a closed position against the valve seat when the pressure responsive member is extended away from the inlet by increasing 35 pressure of the fluid in response to increasing depth of the fluid and thereby limiting increase 40 of pressure upon the pressure responsive member, and a circuit for the pump-operating mechanism including a stationary contact in the casing and a movable contact connected with the spring loaded valve and moved into circuit-closing 45 engagement with the stationary contact when the valve is closed.

13. A device for controlling an electrically actuated pump-operating mechanism comprising a casing adapted to be submerged vertically in a 50 body of liquid subject to variations in depth and

consequent pressures, said casing having an inlet and a valve seat associated therewith, a spring loaded valve movable inwardly of said casing to a closed position against the valve seat and urged outwardly to an open position, a pressure responsive member in said casing enclosing the inner end of the inlet and connected with the valve and serving to shift the valve to a closed position against the valve seat when the pressure responsive member is extended away from the inlet by increasing pressure of the liquid in response to increasing depth of the liquid and thereby limiting increase of pressure upon the pressure responsive member, and a circuit for the pump-operating mechanism including a stationary contact in the casing and a movable contact connected with the said spring loaded valve and moved into circuit-closing engagement with the stationary contact when the valve is closed.

14. A device for controlling opening and closing of a switch for the circuit of a motor for a well pumping operating mechanism and which device is unitary in character, and as such, inserted vertically in a well and immersed in liquid 1 in the well and subject to the pressure conditions within the well, the said device including a casing having an inlet, a spring loaded valve in the casing yieldably held open, the valve including a valve stem carrying a valve member, a seat for said valve member, a bellows concentrically disposed about said valve stem and exposed to the compressive forces of said spring for holding the valve open, a switch actuating member carried by said bellows, a pressure tube carried by the said device and enclosing a liquid that is in contact with the said bellows interiorly thereof, the said pressure tube being subject to the pressures within a well and effecting expansion of said bellows for expanding the same and imparting movement to the valve and its stem for closing the valve at a predetermined pressure and simultaneously closing the switch and thereby causing the motor of the pump operating mechanism to be set in motion.
